Attorney.

Patented Feb. 12, 1924.

UNITED STATES PATENT OFFICE.

OSCAR T. ANDERSON, OF WATERLOO, IOWA, ASSIGNOR TO CHAMBERLAIN MACHINE WORKS, OF WATERLOO, IOWA.

WRINGER.

Application filed December 13, 1921. Serial No. 522,040.

To all whom it may concern:

Be it known that I, OSCAR T. ANDERSON, a citizen of the United States of America, and a resident of Waterloo, Blackhawk County, Iowa, have invented certain new and useful Improvements in Wringers, of which the following is a specification.

My invention relates to improvements in wringers, and the objects of my improvements are these; first, to so design the bearing-seats of the upright parts of the frame and the roller bearing-boxes therein that the latter may be removed upwardly from said bearing-seats without difficulty, and second, to so construct the upper closure of the frame above the rollers of laterally swinging parts to permit of such easy removal of the bearing-seats, and to supply said laterally moving parts with roller-spring tensioning means and also with easily manually actuatable releasable interlocking connections which may serve as safety means in quickly relieving the spring tension on the uppermost roll in case of necessity while separating said interlocking connections.

These objects I have accomplished by the means which are hereinafter described and claimed, and which are illustrated in the accompanying drawings, in which Figs. 1 and 2 are like side elevations of my improved wringer showing respectively the laterally swinging top closure parts in their closed and in their opened positions. Fig. 3 is a top plan of the wringer as shown in said Fig. 2. Fig. 4 is a top plan view of the wringer with said top closure parts closed and secured together, and Fig. 5 is an end elevation of the wringer with said top closure parts closed. Fig. 6 is a side elevation of the wringer showing the top closure parts swung apart to open positions, and showing the roller bearing seats lifted and removed entirely clear of the wringer frame.

Similar numerals of reference denote corresponding parts throughout the several views.

My improved wringer may be made of any suitable material or of different dimensions and with various modifications in its parts and their relative arrangements, without departing from the invention. As illustrated herein, I have shown a preferred construction wherein the frame and other parts, except the coacting resilient rubber

rollers 20 and 21, are all of metal, mostly of steel.

The rigid U-shaped main frame comprises like outwardly channelled uprights 1 fixedly mounted on the extremities of a horizontal tubular beam 2. These uprights are connected midway of their heights on opposite sides by horizontal brace-bars 3. The upper parts of the webs of the uprights 1 have open top longitudinal openings with outwardly directed and oblique side flanges 23, and like inwardly flanged pieces 22 are welded or otherwise secured on the inner faces of the uprights and together with the flanged parts 23, serve as vertical slideways to receive the anti-frictional bearing boxes 24 and 25 of the shafts or spindles of said rubber rollers 20 and 21. A bifurcated flanged plate 18 is secured to each box 24 and its lower forked part is positioned astride the shaft of the lower roller 21 and serves as a closure or guard adjacent the inner faces of said uprights. A rectangular plate 19 extends upwardly from each box 24 and has a horizontal slot to removably receive an end of an upwardly bowed plate-spring 16. A housing plate covering the upper part of the hollow between the flanges of the uprights 1 and upon these plates 17 like closure-bars 4 and 5 are with their downward extensions 6 swingingly pivoted at 7 to swing to and from each other laterally.

Each closure-bar or part 4 or 5 is bowed upwardly and shaped with an angular cross section whereby when these parts are closed together they form a closed top open bottom housing for the middle upper part of the spring 16. The numeral 9 denotes an arcuate bar having one end hinged at 8 medially to the outer face of the closure part 5 to swing to and from across it and over and fitting both parts 4 and 5 when the latter are closed together as shown in Fig. 5. A medial opening in the bar 9 is interiorly threaded to receive a tensioning screw 10 whose lower part traverses registering semi-circular notches below in said parts 4 and 5, so that the screw may be manually used to engage the spring 16 thereunder and place it under tension to thus yieldingly force the uppermost roller 20 toward the lower roller 21. Hinging at 8 of the curved bar 9 insures quick engagement or disengagement with the closure parts 4 and 5 without interfer-

ence, as in certain emergencies it may be important that the parts 4 and 5 may be instantly thrown apart.

An open top boxing 11 on the closure part 4 contains a cross pintle 15 on which is pivoted the lower end of a hand lever 12 having an angular catch 14 which, when the latter is swung upwardly, may releasably engage a fixed pin 13 on the hither side of the curved bar 9 to interlock the parts 4 and 5 together detachably. As the handle part of the lever 12 is terminally widened and shaped to overhang the part 4, it may be operated to disengage from the pin 13 by manual pressure downwardly. The compressed spring 16 immediately reacts upwardly sufficiently to throw the parts 4 and 5 outwardly oppositely beyond their centers of gravity to become lowered to the positions shown in the lower part of Fig. 6. Even if the spring reaction is not enough to separate these parts to that extent, the upper roller is nevertheless relieved from tension instantly so that this improvement becomes an efficacious safety device for the operator, in preventing injury to the person or garments when accidentally drawn between the rollers. As heretofore stated, this construction of the widely separable top closure part gives complete clearance to permit of the upward complete withdrawal from the frame of the spring and upper roller with its boxings as is illustrated in the upper part of said Fig. 6. The removable parts of the wringer are thus made easily demountable for cleaning, renewals or repairs.

Having described my invention, what I claim as new and desire to secure by Letters Patent, is:

1. The combination with spaced frame-uprights of a wringer, of parts hinged to the uprights to swing to and from each

other laterally, coacting rollers, resilient means bearing upon said rollers, adjustable means mounted on one of said parts to releasably tension said resilient means, and means for releasably locking said parts when closed together.

2. In combination, a wringer having rigidly connected spaced uprights provided with open top seats, upwardly-removable bearings in said seats, and resilient means removably mounted upon said bearings, a pair of elements having their end parts hingedly connected to opposite parts of the tops of said uprights to swing to and from each other laterally, adjustable tension-producing means mounted on one of said elements to tension said resilient means when the elements are closed together, and means for releasably locking said elements together.

3. In a wringer, a frame having rigidly basally connected uprights, said uprights having bearing-recesses open at the top, journal-boxes mounted in and upwardly removable from said recesses, coacting rollers mounted rotatably in said boxes, top-closing means comprising a pair of elements hinged to said uprights to swing to and from each other laterally, resilient means mounted to bear upon the uppermost roller yieldingly, means mounted adjustably on one of said elements to compress said resilient means, and releasable locking connections between said elements including a releasing-member operable manually to disconnect said elements to allow the resilient means to reactively throw apart said elements and relieve the tension of said resilient means upon said uppermost roller.

Signed at Waterloo, Iowa, this 3d day of Dec. 1921.

OSCAR T. ANDERSON.
